[57] CLAIM

The ornamental design for a combined magnifier and ruler, as shown and described.

DESCRIPTION

FIG. 1 is a top plan view of the combined magnifier and ruler showing my new design;

FIG. 2 is a front elevational view thereof; the rear elevational view being a mirror image thereof;

FIG. 3 is a bottom plan view thereof;

FIG. 4 is an end elevational view thereof; the opposite end being a mirror image thereof; and,

FIG. 5 is an enlarged end elevational view thereof.
